UNITED STATES PATENT OFFICE.

WILLIAM P. THOMSON, OF ALTOONA, PENNSYLVANIA.

DESIGN FOR A SPIKE-EXTRACTING IMPLEMENT.

SPECIFICATION forming part of Design No. 30,111, dated January 31, 1899.

Application filed December 2, 1898. Serial No. 698,116. Term of patent 14 years.

To all whom it may concern:

Be it known that I, WILLIAM P. THOMSON, a citizen of the United States, residing at Altoona, in the county of Blair and State of Pennsylvania, have invented and produced a new and original Design for Spike-Extracting Implements, of which the following is a full, clear, and exact description, reference being had to the accompanying drawings, of which—

Figure 1 is an edge elevation of a spike-extracting implement embodying my design. Fig. 2 is a side elevation.

The leading feature of my design relates particularly to the form of the foot portion of the implement, which is integral with the handle portion 1. Said feature of my design consists of such foot portion 2, whose plane base 2^a forms with the line of the major axis 20 of the handle an obtuse angle at the front and an acute angle at the rear. The front or toe portion 3 extends some distance beyond the line of the front side of the handle and gradually diminishes in thickness to the point, 25 as seen in Fig. 2. The sides of the ends of said toe portion are beveled at 3^a, as seen in

Figs. 1 and 3, and there is a notch 3^b in the end of said toe portion having flaring sides 3^c. The under side of the end of the toe is beveled upwardly at 3^d to form an acute angle with the upper face or line of the extremity of the toe, as seen in Fig. 2. The rear face 4 of the heel portion is plane and meets the rear end of the base portion 2^a at an angle, the apex of which is some distance 35 to the rear of the line of the rear or under side of the handle portion, forming an obtuse angle with the latter. The said rear face of the heel portion is substantially at right angles to a line bisecting the angle formed 40 by a forward extension of the base-line 2^a and upper line 3^c of the toe portion.

I claim—

The design for a spike-extracting implement substantially as shown and described. 45

In testimony whereof I have hereunto affixed my signature this 10th day of November, A. D. 1898.

WILLIAM P. THOMSON.
